(57) **CLAIM**

The ornamental design for a snap buckle, as shown and described.

DESCRIPTION

FIG. 1 is a right side view of a snap buckle, showing our new design;

FIG. 2 is a bottom plan view thereof;

FIG. 3 is a left side view thereof;

FIG. 4 is a front view thereof;

FIG. 5 is a top plan view thereof;

FIG. 6 is a rear view thereof; and,

FIG. 7 is a top perspective view thereof.

The portions of the snap buckle shown in broken lines form no part of the claimed design.

1 Claim, 7 Drawing Sheets
